MACHINE FOR GRINDING AND TURNING
BRAKE DRUMSOloy J. E. Olsson, Minneapolis, Minn., assignor
to Storm Manufacturing Company, Inc., Min-
neapolis, Minn., a corporation of Minnesota

Application December 26, 1940, Serial No. 371,813

2 Claims. (Cl. 29—28)

This invention has relation to a lathe, or like machine, designed to be more especially useful to the purposes of grinding and turning brake drums.

An object of the invention is to provide a lathe, or grinding and turning machine, which will be of novel and improved construction.

A further object is to provide a lathe, or grinding and turning machine, of the type herein presented wherein will be incorporated various improved features and characteristics of construction novel both as individual entities of said lathe, or grinding and turning machine, and in combination with each other.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawings forming a part of this specification,

Fig. 1 is a top plan view of a machine in which the features and characteristics of the invention are incorporated;

Fig. 2 is a side or end elevational view of the machine of Fig. 1, with the brake drum and a part of the support for said brake drum removed and the grinding tool supporting shaft in section;

Fig. 3 is a detail sectional view, taken on line 3—3 in Fig. 2;

Fig. 4 is an enlarged sectional view of the brake drum support, taken substantially on line 4—4 in Fig. 1;

Fig. 5 is a sectional view detailing gearing of the machine, taken substantially on line 5—5 in Fig. 1, or as on line 5—5 in Fig. 4;

Fig. 6 is a detail sectional view, taken as on line 6—6 in Fig. 5;

Fig. 7 is an enlarged sectional view, taken substantially on line 7—7 in Fig. 2;

Fig. 8 is a detail sectional view, taken as on line 8—8 in Fig. 7;

Fig. 9 is an enlarged fragmentary side or end elevational view, partially in section, disclosing parts of the machine in positions other than those in which said parts are disclosed in Figs. 1 and 2;

Fig. 10 is an enlarged fragmentary elevational

view, partially in section, of mechanism for controlling operation of the machine;

Fig. 11 is a detail sectional view of latch means of said control mechanism, taken on line 11—11 in Fig. 10;

Fig. 12 is a view corresponding generally with the disclosure of Fig. 11, but showing the latch means in a different position;

Fig. 13 is a fragmentary elevational view further detailing said latch means;

Fig. 14 is a detail view disclosing the relation of the cutting tool of the machine to a brake drum when said cutting tool is positioned to perform a turning operation upon said brake drum;

Fig. 15 is a view corresponding generally with the disclosure of Fig. 4, but showing a brake drum support of modified construction adapted to be employed in the machine; and

Fig. 16 is an enlarged fragmentary sectional view detailing features included in the disclosure of Fig. 15.

With respect to Figs. 1 to 14 of the drawings and the numerals of reference thereon, a frame for the grinding and turning machine is denoted generally at 20. Said frame 20 rigidly supports an extension portion 21 of the frame which in turn rigidly supports an electric motor 22.

The frame 20 also supports a carriage 23 adapted to be reciprocated upon said frame in direction longitudinally thereof and transversely of the shaft 24 of the electric motor 22. More explicitly, said carriage 23 includes a base portion 25 thereof slidably movable over an adjacent surface 26 of the frame 20, and oppositely disposed, oblique or bevel flange portions 27, 27 thereof slidably movable over oblique or bevel surfaces 28, 28 of the frame 20 which are opposite said base portion 25 and said surface 26.

Stated otherwise, the oppositely disposed, oblique or bevel flange portions 27, 27 are spaced from the base portion 25, as well as from each other, and extend inwardly in oblique or bevel relation to said base portion 25, to provide oppositely disposed guideways 29, 29 of the carriage 23 extending longitudinally of the frame of the machine in which opposite side edge portions 30, 30 of the frame 20 are snugly, but slidably, situated. The carriage 23 is adapted to be reciprocated longitudinally of the frame by slidable movement of

said carriage and its oppositely disposed guideways 29, 29 along the opposite side edge portions 30, 30 of said frame.

The carriage 23 supports a bracket member 31 adapted to be adjusted transversely of the frame 20 and perpendicularly to the direction in which

said carriage is reciprocable along said frame. More explicitly, said bracket member 31 includes a base portion 32 thereof slidably movable over an adjacent surface 33 of the carriage 23, and oppositely disposed, oblique or bevel flange portions 34, 34 thereof slidably movable over oblique or bevel surfaces 35, 35 of said carriage which are opposite said base portion 32 and said surface 33. Stated otherwise, the oppositely disposed, oblique or bevel flange portions 34, 34 are spaced from the base portion 32, as well as from each other, and extend inwardly in oblique or bevel relation to said base portion 32, to provide oppositely disposed guideways 36, 36 of the bracket member 31 extending transversely of the carriage 23 in which opposite side edge portions 37, 37 of said carriage are snugly, but slidably, situated. The bracket member 31 is adapted to be adjusted transversely of the carriage 23 by slidable movement of said bracket member and its oppositely disposed guideways 36, 36 along the opposite side edge portions 37, 37 of said carriage.

Said bracket member 31 supports, or includes, several, or a number of, parts of the grinding and turning machine, and mechanism is included for accomplishing sliding adjustment of the bracket member, with parts supported thereby, transversely of the carriage, and for causing said bracket member to be secure at any position to which set crosswise of said carriage.

As disclosed, the bracket member 31 includes an integral arm 38 disposed perpendicularly to the base portion 32 of said bracket member and situated adjacent the side portion 39 of the carriage 23 which is opposite the electric motor 22, in spaced relation to said side portion 39 and in alining relation with said carriage. An adjusting member or screw 40 is rotatably mounted and fixed against longitudinal movement, as indicated at 41, in the arm 38, and an end portion 42 of said adjusting member or screw 40 is threadably mounted, as at 43, in said side portion 39 of the carriage. A slot 44 in said carriage 23 at the side of the portion 39 opposite the arm 38 provides clearance for longitudinal movement of the adjusting member or screw 40, as will be evident. Said adjusting member or screw 40 is arranged perpendicularly to said arm 38 and parallelly of, or in alinement with, the carriage 23, and the end portion of the adjusting member or screw 40 which is opposite the threaded end portion 42 fixedly supports a hand piece 45 through the instrumentality of which said adjusting member or screw can be rotated, thus to accomplish adjustment of the bracket member 31 transversely of the frame 20 and the carriage 23. Clearly, by turning adjustment of the member or screw 40 in one direction, it will be caused to move inwardly of the machine, thus to cause the bracket member 31 to be adjusted inwardly, and by turning adjustment of said member or screw in opposite direction, it will be caused to move outwardly of said machine, thus to cause said bracket member to be adjusted outwardly. Obviously, the bracket member 31 will be secured in fixed relation to the carriage 23 at any location along the width of said carriage to which said bracket member may be adjusted.

Mechanism also is included for supporting and rotating a brake drum, or the like, to be ground and turned in the machine, as well as for accomplishing reciprocation of the carriage 23, together with the bracket member 31 and the

parts supported, or included, by said bracket member, upon the frame 20.

The driven shaft 24 of the electric motor 22 is at the side of the frame 20 and the carriage 23 which is opposite the hand piece 45. A gear casing 46, constituted as a part of the frame of the machine, suitably and conveniently rotatably supports a driving shaft 47 disposed transversely of said frame and parallelly of the motor shaft 24 in spaced relation to said motor shaft. An outer end portion of the driving shaft 47 fixedly carries step pulleys 48 which are alined with step pulleys 49 fixed upon the motor shaft 24, and a belt 50 rides the pulleys 48 and 49 in customary fashion. An intermediate portion of said driving shaft 47 fixedly carries a worm 51 which meshes with a worm wheel 52.

A hollow work spindle 53 is suitably and conveniently rotatably mounted, as by Timken bearings 54, in the gear casing 46, and said hollow work spindle is suitably and conveniently fixed against endwise or longitudinal movement in said gear casing. Said worm wheel 52 is situated in the gear casing 46 and is keyed, as at 55, upon an inner reduced portion 56 of the hollow work spindle. A small gear 57, also keyed upon said hollow work spindle at 55, is situated at the side of the worm wheel 52 opposite the Timken bearings and in contiguous relation with a hub 58 integral with said worm wheel. A washer 59 is disposed between said worm wheel 52 and the adjacent Timken bearing 54, and a spacing sleeve 60 is slidably situated upon said reduced portion 56 of the hollow work spindle at the side of the small gear 57 which is opposite the hub 58. Lock nuts 61 adjacent the end of the spacing sleeve 60 opposite the small gear 57 and engaged with an external thread 62 upon the reduced portion 56 are adapted to be turned home against said spacing sleeve 60 thus to cause the worm wheel 52 and the hub thereon and the small gear 57 to be clamped against each other and between the washer 59 and the spacing sleeve 60 and said worm wheel and small gear to be fixed against movement longitudinally of the hollow work spindle 53, as will be apparent.

The small gear 57 meshes with a second small gear 63 fixed upon a short shaft 64 suitably and conveniently rotatably mounted in the gear casing 46, and said short shaft 64 fixedly carries a worm 65 which meshes with a worm wheel 66 fixed upon a second short shaft 67 suitably and conveniently rotatably mounted in the gear casing and disposed at right angle relation to the short shaft 64. A stub shaft 68, suitably and conveniently rotatably mounted in said gear casing and disposed in parallel relation to the second short shaft 67, fixedly carries a larger gear 69 and a smaller gear 70 at its intermediate portion and a bevel gear 71 at its free end. Spaced apart smaller and larger gears, denoted 72 and 73, respectively, are splined to the second short shaft 67 to rotate with said second short shaft and to be movable longitudinally thereon, either to be brought, respectively, into meshing relation with the larger gear 69 and the smaller gear 70, or to be removed from engagement with said larger and smaller gears 69 and 70.

A gear shifter device is for accomplishing movement of the smaller and larger gears 72 and 73 longitudinally of the second short shaft 67, selectively to cause said gear 72 to be engaged with the gear 69, or said gear 73 to be engaged with the gear 70, or both of the gears 72 and 73 to be removed from engaging relation with said

gears 69 and 70. Said gear shifter device includes a shifter rod 74 which is mounted, as at 75, in the gear casing 46 for longitudinal sliding movement. Said shifter rod 74 fixedly supports a finger piece 76 upon its outer end to be manipulated to accomplish longitudinal adjustment of the shifter rod, and also fixedly supports a shifter arm 77 upon its inner end. The shifter arm 77 includes a fork portion 78 thereof which lies between spaced apart annular elements 79, 79 slidable upon the second short shaft 67 and rigid with the smaller and larger gears 72 and 73. The construction and arrangement are such that the annular elements 79, 79 are rotatable with said gears 72 and 73 and the second short shaft 67, when these are rotated, and relatively to the shifter arm 77 and its fork portion 78. It will be obvious that when the shifter rod is in inserted position, as in Fig. 5, the larger gear 73 will be in mesh with the smaller gear 70, that when said shifter rod is in withdrawn position, the smaller gear 72 will be in mesh with the larger gear 69, and that when the shifter rod is in intermediate position, said gears 73 and 72 will be removed from engagement with said gears 70 and 69, respectively. As disclosed more clearly in said Fig. 5, the shifter rod 74 is provided with three spaced apart slots 80, and a retaining element 81 is adapted to be resiliently pressed by a coil spring 82 into each of said slots thus to insure that said shifter rod 74 will stably remain at each of its adjusted positions against the possibility of accidental displacement. The construction and arrangement are such that the shifter rod readily can be slid or moved to and away from any of its intended positions.

A feed member or screw 83 is suitably and conveniently rotatably mounted, as represented generally at 84, in the frame 20. Means (not shown) will of course be included to preclude longitudinal movement of said feed member or screw 83. Said feed member or screw 83 is disposed longitudinally of said frame 20 and includes an externally threaded portion 85 thereof which meshes with an internally threaded portion 86 of the carriage 23. Also, the feed member or screw 83 extends through the gear casing 46 and is disposed in adjacent relation to the bevel gear 71, as well as in perpendicular relation to the stub shaft 68 which fixedly carries said bevel gear 71.

The feed member or screw 83 is adapted to be rotated in either direction, thus to cause the carriage 23 to be fed forwardly or rearwardly, as may be predetermined, through the instrumentality of the bevel gear 71. To this purpose, clutch means 87 is provided. More explicitly, spaced apart, oppositely disposed bevel gears, indicated 88 and 89, respectively, are in surrounding, nomally free relation to the feed member or screw 83 and in engaging relation with opposite side portions or sides of the bevel gear 71. While said feed member or screw 83 normally is freely rotatable within the bevel gears 88 and 89, said just mentioned bevel gears are suitably and conveniently fixed against movement longitudinally of the feed member or screw to be constantly in mesh with the bevel gear 71. The clutch means 87 is slidably mounted upon the feed member or screw 83 between the bevel gears 88 and 89 and is splined, as at 90, to said feed member or screw. The bevel gear 88 includes spaced apart, internal, longitudinally extending ribs 91, the bevel gear 89 includes spaced apart, internal, longitudinally extending ribs 92, and

said clutch means 87 includes spaced apart, external ribs 93 adapted to be aligned with the longitudinally extending ribs 91 and 92. The bevel gears 88 and 89, including their ribs, are spaced from each other a distance slightly greater than the length of the ribs 93, and said ribs 93 as shown extend substantially the full width of the clutch means 87.

Devices are included selectively for positioning the ribs 93 of said clutch means 87 to be situated clear of the ribs 91 and 92, as in Fig. 6, so that both of the bevel gears 88 and 89 will be freely rotatable upon the feed member or screw 83 with rotation of the stub shaft 68 and the bevel gear 71, for positioning said ribs 93 in engagement with the ribs 91 so that said feed member or screw will be rotated in direction to correspond when said stub shaft 68 and bevel gear 71 are rotated, and for positioning the ribs 93 in engagement with the ribs 92 so that the feed member or screw will be rotated in direction to correspond, or in direction opposite that in which said feed member or screw rotates when the ribs 93 and 91 are engaged, when the stub shaft 68 and bevel gear 71 are rotated. The feed member or screw 83 obviously will be turned with turning of the bevel gear 71 while the ribs 93 are engaged with either the ribs 91 or the ribs 92. When the ribs 93 and 91 are engaged, the bevel gear 88 is clutched to the feed member or screw 83 and said feed member or screw is free to rotate within the bevel gear 89, and when the ribs 93 and 92 are engaged, the bevel gear 89 is clutched to the feed member or screw and said feed member or screw is free to rotate within the bevel gear 88. The devices for accomplishing sliding movement of the clutch means 87 along the feed member or screw 83 are best disclosed in Figs. 1, 5 and 6. A manipulating piece 94, rotatably mounted upon the gear casing 46, carries a bifurcated bar 95 which straddles a pin 96 rigid with a wing 97 fixed to said clutch means 87. The wing 97 is slidably supported upon a rod 98 suitably and conveniently mounted within said gear casing and disposed parallel with the feed member or screw 83. Said wing 97 is adapted to be slid longitudinally of the rod 98 by rotational actuation of the manipulating piece 94, thus to cause the clutch means 87 to be moved longitudinally along said feed member or screw 83. Said manipulating piece 94 may include a retaining element 99, similar to the retaining element 81, engaged against the gear casing 46 for insuring that the clutch means 87 stably will remain at any adjusted position to which set.

A hand wheel 100 fixed upon a free end of the feed member or screw 83 at a side of the gear casing 46 which is opposite the carriage 23 is for accomplishing manual rotational actuation of said feed member or screw. Evidently, when the clutch means 87 is in neutral position, as in Fig. 6, the feed member or screw can be freely rotated in either direction through the medium of said hand wheel 100. The electric motor 22 is adapted to cause said feed member or screw 83 to be driven, through the gearing before described, at comparatively slow rates of speed. By rotational actuation of the hand wheel 100, the feed member or screw evidently can be turned much more rapidly than intended to be mechanically driven, thus to enable an operator of the machine readily and quickly to adjust the carriage 23 forwardly and rearwardly, or toward and away from the work to be accomplished.

The Timken bearings 54 maintain the hollow work spindle 53 in exact parallel relation with the guideways 29, 29 provided by the carriage 23, as well as in precise parallel relation with the feed member or screw 83, at a side of said guideways 29, 29 and said feed member or screw. An arbor 101 for supporting a brake drum 102 to be ground and turned includes a circular, taper part 103 of said arbor adapted to be seated in a longitudinal opening 104 through the hollow work spindle 53. More explicitly, a part 105 of the opening 104, defining the end portion of said opening opposite the worm wheel 52, has shape similar to that of the circular, taper part 103 of the arbor 101 to which said part 103 is adapted to be snugly fitted. A draw rod 106, including a head 107 at its outer end and an externally threaded portion 108 at its inner end portion, is for removably retaining the arbor 101 in rigid relation to the hollow work spindle 53. As disclosed, the draw rod 106 extends longitudinally through the opening 104, the externally threaded portion 108 of said draw rod is removably engaged with an internal thread 109 in the inner end of the arbor 101, and the head 107 of the draw rod is engaged against the end of the reduced portion 56 of said hollow work spindle 53 which is opposite the brake drum 102. Obviously, by turning the head 107 in one direction the arbor 101 can be made rigid with the hollow work spindle, and by turning said head 107 in opposite direction the draw rod 106 can be released from said arbor, thus to render the arbor removable from said hollow work spindle. When the head 107 of the draw rod is turned down against the reduced portion 56 of the hollow work spindle, the arbor 101 and said hollow work spindle evidently are secured to each other to be constituted as a unitary entity.

As disclosed, the brake drum 102 is rigidly secured upon the end portion of the arbor 101 which is opposite the hollow work spindle 53 by the employment of spaced apart collars 110 and 111 situated at and against the opposite end portions, respectively, of a hollow hub 112 of said brake drum. The collar 110 may be adjustable along and made secure with the arbor 101 in any suitable and convenient manner, and the collar 111 may be fastened against the hollow hub 112 by means of a nut 113 upon the outer end portion of the arbor 101. The construction and arrangement will be such that when the nut 113 is turned home, said hollow hub 112 will be rigidly engaged by the collars 110 and 111 to cause the brake drum 102 to be rigidly supported upon the arbor 101 with its part to be ground and turned in precise concentric relation to said arbor and the hollow work spindle.

It will be apparent that with rotation of the hollow work spindle 53, by the electric motor 22 and through the instrumentality of a pulley 49, the belt 50, a pulley 48, the driving shaft 47, the worm 51 and the worm wheel 52, there will be rotation of the arbor 101 when rigid with said hollow work spindle and of the brake drum 102 when rigid with said arbor.

A cylindrical tool post 114 of the machine is situated at the midwidth of the bracket member 31 and is rotatably supported by said bracket member in upstanding, perpendicular relation thereto. As shown, the lower end of the cylindrical tool post 114 includes an annular flange 115 rotatably fitted in an annular opening 116 in the base portion 32 and adapted to be slideable along the horizontal surface 33. The lower por-

tion of said cylindrical tool post is snugly, but rotatably, fitted, at 117, in said base portion 32, and a collar 118 fixed to the tool post and engaged against the upper surface of the bracket member 31 cooperates with the annular flange 115 to fix said tool post against longitudinal movement.

Said bracket member 31 includes an annular reduced portion 119 at its outer or upper side 10 in surrounding, concentric relation to the cylindrical tool post, and a swivel plate 120 is rotatably mounted upon said annular reduced portion 119 to rest upon and be slideable over the outer or upper surface of the bracket member. The swivel plate 120 includes an arcuate slot 121 in spaced relation to the annular reduced portion 119 and disposed transversely of said swivel plate and of the bracket member 31, and a screw bolt 122 passing through said arcuate slot 121 and entering 15 said bracket member is for releasably fixing the swivel plate at any position to which slidably adjusted upon the bracket member about the reduced portion 119 as an axis.

A grinding tool holder of the machine is indicated at 123, and a turning tool holder is denoted at 124.

The turning tool holder 124 is rotatably mounted upon the cylindrical tool post 114 in contiguous relation to the swivel plate 120. More explicitly, 30 said turning tool holder includes a body portion thereof having its base contiguous with and slideable over said swivel plate, and an upstanding, hollow tubular portion 125 thereof, at a side of said body portion, snugly and rotatably situated upon an intermediate portion of the cylindrical tool post in adjacent relation to, or contiguous relation with, the collar 118.

The grinding tool holder 123 also is rotatably mounted upon said cylindrical tool post 114, and 40 is adapted to be in contiguous relation with the swivel plate 120, or in spaced relation to said swivel plate. More explicitly, said grinding tool holder includes a body portion thereof the base of which is adapted to be in contiguous relation with the swivel plate 120, as in Figs. 2 and 7, or in 45 spaced relation to said swivel plate, as in Fig. 9, and an upstanding hollow tubular portion 126 thereof, at a side of an upper part of said body portion, snugly and rotatably and longitudinally slidably situated upon said cylindrical tool post 114 at location above the upstanding hollow tubular portion 125.

Said turning tool holder 124 suitably and conveniently supports, as at 127, a turning tool 128 including a cutter 129 adapted to be engaged with the internal surface of a brake drum to be turned in the manner as best disclosed in Fig. 14. When 55 said cutter 129 is in operative position the turning tool holder 124 and the grinding tool holder 123 are relatively situated as in Fig. 9. That is to say, said grinding tool holder is elevated to a position where it is in spaced relation to the swivel plate 120 at elevation above and clear of said turning tool holder when the turning tool 60 is to be put to work.

Said grinding tool holder 123 suitably and conveniently supports, as at 130, a supporting shaft 131 which rigidly carries a grinding tool 132 adapted to be engaged with the internal surface of a brake drum to be ground in the manner as best disclosed in Fig. 1. When 65 said grinding tool 132 is in operative position the grinding tool holder and the turning tool holder are relatively situated as in Figs. 1, 2 and 7. That is to say, said grinding tool holder is situated in contigu-

ous relation with the swivel plate 120 at the elevation of said turning tool holder when the grinding tool is to be put to work.

It will be seen that whereas the turning tool holder 124 is located in Figs. 1 and 2 at the side of the tool post 114 adjacent the hand piece 45, with the turning tool 128 and its cutter 129 extending in direction away from the brake drum, said turning tool holder is located in Fig. 9 at the side of said tool post opposite said hand piece, with the cutter of said turning tool extending in direction toward said brake drum. In said Fig. 9, numeral 133 represents a spring-pressed index pin carried by the turning tool holder 124 disposed in an index opening 134 in the swivel plate 120, and 135 denotes an index opening in said swivel plate situated at 180° from the index opening 134. In practice, said turning tool holder is rotated upon the swivel plate until the index pin 133 enters the index opening 134 when it is the intention to accomplish a turning operation in the machine, and is rotated until said index pin enters the opening 135 when it is the intention to perform a grinding operation. The turning tool holder 124 is in Fig. 2 spaced at 180° from its position as in Fig. 9.

Also it will be seen that the grinding tool holder 123 is located in Figs. 1 and 2 at the side of the tool post 114 opposite the hand piece 45 with the grinding tool 132 upon the supporting shaft 131 disposed in grinding relation to the brake drum to be operated upon. In said Figs. 1 and 2, the grinding and turning tool holders are in parallel, contiguous relation, the tubular portion 126 is resting upon the tubular portion 125, and the index pin 133 is in the index opening 135 thus to cause the grinding tool 132 to be in its proper grinding relation to said brake drum. That is to say, the turning tool holder when set at its inoperative position constitutes means in the machine for causing the grinding tool holder to be situated at proper grinding position of the grinding tool.

The disclosure includes mechanism for raising and lowering, or longitudinally moving, the grinding tool holder 123 along the cylindrical tool post 114 and for insuring that said grinding tool holder will stably remain at any position to which moved. A rack 136 extends longitudinally of said tool post, and an operating spindle 137 is rotatably mounted, as at 138, in the grinding tool holder. Said operating spindle includes a gear 139 in mesh with the rack 136 and an operating crank 140. Said grinding tool holder 123 is fixed, as at 141, against rotational movement upon the tool post 114 thus to insure the set relation of said rack 136 and said gear 139, and a spring-pressed element 142 carried by the grinding tool holder and engaged with said tool post is for precluding movement of said grinding tool holder along the tool post save when such movement is intentional.

The disclosure also includes devices for fastening each of the grinding tool holder and the turning tool holder when in operative position rigidly against the swivel plate 120 and the bracket member 31. Of said devices, numeral 143 designates a part-cylindrical spacer adapted to be removably situated upon the tool post 114, and 144 denotes a clamping nut upon the outer or free end of said tool post. In Figs. 2 and 7 the part-cylindrical spacer 143 is located between the clamping nut 144 and the tubular portion 126 of the grinding tool holder 123, and said clamping nut is turned home against the

upper end of said part-cylindrical spacer to cause the lower end of the spacer to be tight against said tubular portion 126 thus to cause the grinding and turning tool holders and the swivel plate 120 to be fixed upon said bracket member 31. In Fig. 9 said part-cylindrical spacer 143 is located between the base of the grinding tool holder and the tubular portion 125 of the turning tool holder, and the clamping nut 144 is turned home against the upper end of the tubular portion 126 of said grinding tool holder to cause said tool holder and the swivel plate to be fixed upon the bracket member.

The supporting shaft 131 and the grinding tool 132 are adapted to be rotated through the instrumentality of a second electric motor, represented at 145, adjustably mounted upon the grinding tool holder 123. To this end, a belt 146 rides a pulley 147 fixed upon the shaft of said electric motor 145 and also rides a pulley 148 fixed upon said supporting shaft 131. The electric motor 145 is fixed upon a bracket 149 pivoted at 150 upon the grinding tool holder 123, and an adjusting screw 151 threaded in said 20 grinding tool holder has its end opposite the head of said adjusting screw engaged against a portion of the bracket 149 spaced from its pivotal support. Evidently, by turning of the adjusting screw 151 said bracket 149 can be moved to 25 situated the electric motor 145 and its shaft with pulley 147 farther from or closer to the pulley 148 thus to adjust the tension of the belt 146.

The electric motors 22 and 145 are adapted to be energized by current from a source (not 30 shown) of electrical energy, and a circuit for said electrical motors is adapted to include an on-and-off switch 159 having an actuating lever 152. Said actuating lever is adapted to be manually moved to the on position of said switch 35 159, and mechanism for controlling operation of the actuating lever, thus to control operation of the electric motors 22 and 145, includes latch means adapted to normally maintain said actuating lever in the closed condition of said switch 40 159, and cam means for causing said latch means to release the actuating lever 152 for movement to the open condition of the switch upon movement of the carriage 23 to both its forward and 45 rearward limit positions.

The on-and-off switch 159 having the actuating lever 152 is mounted upon the frame 20. An operating rod 153 for said actuating lever 152 is 50 slidably mounted in spaced apart bearings 154 and 155 upon said frame and is disposed in parallel, adjacent relation to a guideway 29 of the carriage 23. A bifurcated element 156 rigid with the operating rod 153 straddles said actuating lever 152, and a coil compression spring 157 upon said operating rod and between the 55 bearing 155 and a head 158 on the rod has potential to urge the operating rod to position said actuating lever in the off condition of said switch 159.

A latch element 160 is slidably mounted in a 60 cup-shape member 161 rigid with the frame 20 and is disposed transversely of the operating rod 153. A portion of the latch element at the closed side of the cup-shape member is notched, as at 65 162, a portion of said latch element at the open side of said cup-shape member includes a button 163, and a coil compression spring 164 upon the latch element and between the base of the cup-shape member and the button 163 normally maintains said button at elevation somewhat 70 above the open end of said cup-shape member. 75

Spaced apart cams 165 and 166 are adjustably supported, as at 167, upon a rod 168 fixed to the carriage 23 and disposed parallelly of the operating rod 153. Working surfaces 169 and 170 of said cams 165 and 166, respectively, are in facing relation to each other.

The working surface 169 is adapted to cause the button 163 to be depressed against the resilient action of the coil compression spring 164 when the carriage 23 reaches the limit of its rearward movement, and the working surface 170 is adapted to cause said button 163 to be depressed against the resilient action of said coil compression spring 164 when said carriage reaches the limit of its forward movement. The construction and arrangement are such that when the button 163 is in elevated position, as in Fig. 10, the notched part of the latch element 160 lies in a transverse slot 171 of the operating rod 153 so that the notch 162 is out of alignment with the operating rod, as in Fig. 11, and when said button 163 is depressed by either the working surface 169 or the working surface 170 said notch 162 becomes aligned with said operating rod 153, as in Fig. 12. Upon alignment of the notch 162 with the operating rod, the coil compression spring 157 will of course act to move said operating rod longitudinally thus to remove the transverse slot 171 from the location of the latch element 160 and its notch 162.

In practice, as the carriage 23 comes to rest at either of its limit positions the latch element 160 will become depressed by one of the cam working surfaces 169 or 170, and the operating rod 153 will be longitudinally slid by the coil compression spring 157 so that said operating rod will cause said latch element to be held depressed against the action of the coil compression spring 164 while the machine is at rest. The longitudinal sliding movement of said operating rod caused by the coil compression spring 157 will of course move the actuating lever 152 to the off condition of the switch 159. When the carriage reaches either of its limit positions, the clutch means 87 will be manually operated to cause the direction of feed of the carriage to be reversed. Then, upon manual actuation of the operating rod 153 inwardly against the resilient action of the coil compression spring 157 to cause the actuating lever 152 to be moved to the on condition of the switch 159, the transverse slot 171 will be aligned with the latch element 160 and said latch element obviously will be released from its switch-off position as in Fig. 12 to become situated at its switch-on position as in Figs. 10 and 11 with the commencement of feeding of the carriage and movement of the cam working surface, 169 or 170, which was in engagement with the button 163 in direction away from said button. Attention is called to the fact that the button 163 will be released by either of the cam working surfaces 169 or 170 in response to quite slight feeding movement of the carriage 23, so that the latch means will cause the actuating lever 152 to be fastened in the on condition of the on-and-off switch 159 substantially immediately after the electric motor 22 is set in operation. Of course, either of the cam working surfaces 169 or 170 can be removed from the button 163 by manual rotation of the hand wheel 100. The switch 159 can be placed in the circuit of only one of the electric motors 22 or 145 in an instance where this is desirable.

It will be apparent that brake drums, or the like, can be smoothly and accurately finished

and trued by employment of grinding and turning entities of the nature as hereinbefore described. Also it will be apparent that different types of grinding and turning tools can be employed in the machine. A brake drum, or the like, being operated upon can be rotated at any of several different speeds through the medium of the step pulleys 48 and 49. Additionally, there is provision in the machine for a faster and a 10 slower forward power feed and a faster and a slower rearward power feed of the carriage 23. With increase of the speed of rotation of a brake drum being ground and turned there will be increase of the rate of feed of said carriage 23, and 15 vice versa. As before stated, the hand wheel 100 constitutes means for manually accomplishing forward and rearward feed of the carriage 23.

Attention is called to the fact that the grinding tool 132 and the turning tool 128 with cutter 20 129 can be accurately angularly adjusted to cause a precise operation to be performed upon a brake drum, or the like, supported in the machine simply by rotatably adjusting the swivel plate 120 upon the annular reduced portion 119. 25 Clearly, adjustment of said swivel plate will cause the grinding and turning tools to be angularly adjusted relatively to the work to be done.

In Figs. 15 and 16 there is disclosed a brake drum support of modified construction adapted 30 to be employed in the machine. Parts in said Figs. 15 and 16 similar to parts previously described bear the same reference numerals.

The gear casing 46 rotatably supports the hollow work spindle 53, as by Timken bearings 54, as 35 before set forth. The worm wheel 52 and the small gear 57 are keyed to said hollow work spindle and are fixed against movement longitudinally of the hollow work spindle in the manner as hereinbefore stated.

40 An arbor 172 integral with a brake drum 173 to be ground and turned extends through a longitudinal opening 174 in the hollow work spindle 53. A compound clamp 175 includes a part 176 thereof releasably grasped upon the end portion 45 of said hollow work spindle adjacent the brake drum and opposite the worm wheel 52 and a part 177 thereof releasably grasped upon an enlarged portion 178 of the arbor 172 adjacent said brake drum. The compound clamp 175 is adapted to 50 support the arbor 172 and the part of the brake drum 173 to be operated upon in exact concentric relation with the hollow work spindle 53. A hollow fitting 179 includes an annular portion 180 thereof removably fitted in the free end portion 55 of the reduced portion 56 of the hollow work spindle 53, a flange portion 181 thereof adapted to be engaged against the free end of said reduced portion 56, and an annular externally threaded portion 182 thereof at the outer side of said flange 60 portion 181. The end portion of the arbor 172 opposite the brake drum 173 passes snugly through the hollow fitting 179. A nut 183 includes an internal thread adjustably engaging the external thread upon the annular portion 182, 65 and a split washer 184 is adapted to be removably situated in an annular groove 185 in the free end portion of the arbor 172, between a head 186 of said arbor and the adjacent surface of the nut 183. Evidently, by turning the nut 183 outwardly 70 on the annular externally threaded portion 182 and against the split washer 184, the arbor 172 can be drawn in direction to bring an internal surface of the compound clamp 175 into pressing engagement with the adjacent end of the hollow work spindle 53 to make said arbor rigid with

said hollow work spindle, and by turning said nut 183 inwardly on said annular portion 182 and away from said split washer, the split washer can be released for removal from the annular groove 185, thus to render the arbor 172 removable from the hollow work spindle. When the nut 183 is in pressing engagement with the split washer 184, the arbor 172 and said hollow work spindle are secured to each other to be constituted as a unitary structure.

What is claimed is:

1. In a grinding and turning machine, a frame, a support for an article to be ground and turned rotatably mounted upon said frame, a carriage reciprocable upon said frame, means for rotating said support and for reciprocating said carriage in directions toward and away from said article, a bracket member upon said carriage, means for adjusting said bracket member transversely of the direction of reciprocation of said carriage, a tool post rotatable in said bracket member and slidably supported by said carriage, a first tool holder having a lower body portion thereof adapted to be supported by said bracket member and an upper hollow tubular portion thereof at a side of said body portion slidably mounted on said tool post, a working tool carried by said first tool holder, a second tool holder having a lower body portion thereof supported by said bracket member and an upper hollow tubular portion thereof at a side of said body portion rotatably mounted on said tool post, a working tool carried by said second tool holder, complemental means for adjusting one of said tool holders longitudinally of said tool post, means for rotating one of said

working tools, a part-circular spacer adapted to be removably situated upon said tool post selectively between and above said mentioned hollow tubular portions, and a nut upon said tool post at the side of said hollow tubular portions opposite said bracket member for clamping said part-circular spacer and the hollow tubular portions of said first and said second tool holders against said bracket member.

10 2. In a grinding and turning machine, a supporting member, a tool post rotatable in said supporting member, a first tool holder having a lower body portion thereof adapted to be supported by said supporting member and an upper hollow tubular portion thereof at a side of said body portion slidably mounted on said tool post, a working tool carried by said first tool holder, a second tool holder having a lower body portion thereof supported by said supporting member and an upper hollow tubular portion thereof at a side of said body portion rotatably mounted on said tool post, a working tool carried by said second tool holder, complemental means for adjusting one of said tool holders longitudinally of said tool post, means for rotating one of said working tools, a part-circular spacer adapted to be removably situated upon said tool post selectively between and above said mentioned hollow tubular portions, and a nut upon said tool post at the side of said hollow tubular portions opposite said supporting member for clamping said part-circular spacer and the hollow tubular portions of said first and said second tool holders against said supporting member.

OLOV J. E. OLSSON.
